(57) **CLAIM**

The ornamental design for a chair, as shown and described.

DESCRIPTION

FIG. 1 is a perspective view of a chair showing my new design;

FIG. 2 is a front elevation view of the chair;

FIG. 3 is a rear elevation view of the chair;

FIG. 4 is a left side elevation view of the chair;

FIG. 5 is a top plan view of the chair; and,

FIG. 6 is a bottom plan view of the chair.

The right side elevation view of the chair is a mirror image of the left side elevation view thereof.
